US0D1110189S

(12) United States Design Patent (10) Patent No.: US D1,110,189 S
(45) Date of Patent:  Jan. 27, 2026

(54) JEWELLERY

(71) Applicant: Tomoko Nishiwaki, Tokyo (JP)

(72) Inventor: Tomoko Nishiwaki, Tokyo (JP)

() Term: 15 Years

(21) Appl. No.: 35/523,723

(22) Filed: Jan. 8, 2025

(80) Hague Agreement Data

Int. Filing Date: Jan. 8, 2025

Int. Reg. No.: DM/243410

Int. Reg. Date: Jan. 8, 2025

Int. Reg. Pub. Date: Jan. 24, 2025

(30) Foreign Application Priority Data

Jul. 8, 2024 (JP) ..... 2024-015351 D

(51) LOC (15) Cl. 11-01

(52) U.S. Cl.

USPC D11/81

(58) Field of Classification Search

USPC D11/1, 2, 40, 44, 48, 66, 79, 81, 82, 85,
